MEANS FOR SUPPORTING THREAD
ADVANCING REELS

Richard F. Bergmann, Lakewood, Ohio, assignor
to Industrial Rayon Corporation, Cleveland,
Ohio, a corporation of Delaware

Application June 10, 1941, Serial No. 397,415

14 Claims. (Cl. 242—53)

The present invention relates to improvements in means for supporting thread-advancing thread-store devices such, for example, as thread-advancing reels intended for the handling of thread, filaments, bands, ribbons, etc.

While the thread-advancing thread store devices with which the invention is concerned may be employed for various purposes, they may be used to especial advantage in apparatus for the continuous processing of multiple filament artificial silk thread. The structure of the invention is particularly designed to provide firm support for a thread-advancing thread store device mounted in such apparatus in operable relation to a plurality of similar devices. Among other things, the invention provides improvements in the supporting structure for devices of this kind which are of the cantilever type; i. e., supported from one end.

Most thread-advancing thread store devices function by virtue of an offset and inclined relation between the axes of the members supporting the thread. Due to tensions in the thread, there is a tendency for the axes of the thread-advancing members to become sprung by the 25 stresses exerted by the thread as it traverses the periphery of the device. This is perhaps more common in devices of cantilever construction, in which the thread-advancing members are supported from one end thereof, but may also occur in devices supported from both ends.

The springing action thus exerted by the thread tends to destroy the inclined relationship between the thread-advancing members, bringing their axes into parallel relation. When this takes place, the thread turns pile up in the form of a wide band at the end of the device toward which the thread would normally advance. In practice, the supporting means for individual thread-advancing members have been known to become so 35 badly sprung as to cause altogether excessive wear upon the thread-advancing members and the driving means; obviously, in such circumstances the thread becomes entangled and broken, thus interrupting the operation of the 45 apparatus as a whole.

The present invention provides means for supporting thread-advancing thread store devices and particularly thread-advancing reels in such manner that flexing between the axes of the 50 thread-advancing members is virtually or entirely eliminated. In part, this is accomplished by supporting the thread-advancing members as closely as possible to the unsupported end of the device as a whole. In part, it is accomplished by 55

providing as wide a spacing as possible between the bearings, particularly in thread-advancing reels employing bearings of the anti-friction type. Other novel features of the invention will be apparent as the description of the invention proceeds.

For convenience, the thread-advancing thread store device shown in Figures 1 and 2 of the accompanying drawing takes the form of an cantilever thread-advancing reel employed in the drying of thread or the like. In such drawing, Figure 1 is a sectional elevation showing the supporting means of the present invention. Figure 2 shows a plan of the apparatus of Figure 1.

The thread-advancing reel of the drawing; that is to say, reel 5, operates on what is generally the same principle as the reel shown, described and claimed in Knebusch Patent 2,210,914. It comprises two rigid reel members 6 and 7 of substantially circular cross section which have peripheries formed of spaced longitudinally extending bar members 8 and 9, respectively. The bar members 8 of reel member 6 and bar members 9 of reel member 7 are disposed alternately in interdigitating relation. Reel members 6 and 7 are mounted for rotation about axes which are offset from and inclined to each other so as to cause the reel to operate to advance the thread in spaced generally helical turns from one end of the reel periphery to the other.

The spaced longitudinally extending bar members 8 of reel member 6 are fixed to a hollow cylindrical body portion 11. Body portion 11 of reel member 6 is enclosed at its ends by front and rear closure members 13 and 14, respectively, which closure members serve to support reel member 6 concentrically of shaft 19. At the same time, such closure members cooperate with body portion 11 to form a fluid-tight chamber 12 in reel member 6 for the purpose of receiving a drying medium such, for example, as steam, hot water, hot air, or other similar fluid. Although any suitable drying medium may be used, the one considered best suited for use in the illustrated reel is hot water. If desired, an electrical heating element may be mounted in reel member 6, the heat in such case being supplied from the heating element.

Surrounding shaft 19 and disposed in recesses 15 in the faces of closure members 13 and 14 are two cooperating sealing members 16 and 17. Sealing member 16, which has a wedge-shaped cross section, is preferably made of rubber; sealing member 17, which is characterized by a corresponding wedge-shaped cross section, is pref-

erably made of metal. It is by means of these sealing members 16 and 17 that fluid drying medium is prevented from escaping around shaft 19 from chamber 12. The sealing members not only prevent escape of the drying medium but also, more particularly in that they serve to position reel member 6 on shaft 19, constitute means for insuring positive rotation of reel members 6 by shaft 19.

Disposed within and at the unsupported end of hollow drive shaft 19 is a plug 20 secured thereto by welding, soldering or the like into which plug is threaded a bolt 21 holding washer 22 in place against sealing member 17 at the front end of the reel. A washer 23, disposed on shaft 19 by means of a snap ring 24, bears against outer sealing member 17 at the rear of reel member 6, serving thereby to locate reel member 6 endwise of shaft 19. As the bolt 21 is tightened, it forces the wedge-shaped sealing members 16 and 17 together, thus effectively sealing reel member 6. The tight fit at these points on shaft 19 also provides the necessary engagement of reel member 6 with shaft 19.

Drying medium is conducted to chamber 12 in body portion 11 of reel member 6 through hollow drive shaft 19. When the drying medium enters chamber 12, it heats the surrounding body portion 11, which in turn transmits the heat to the longitudinally extending bar members 8 of reel member 6. Thus the thread being advanced along the thread-bearing periphery of reel 5 is dried. Because of the effectiveness of the sealing means in preventing escape of the heating fluid, there is little or no likelihood of injury to thread stored on the reel.

Reel member 1, which may be termed the eccentric reel member by reason of the fact that it is mounted with its axis in offset and inclined relation to that of reel member 6, comprises bar members 9 formed as a part of a rigid cage-like member. Reel member 1, which, like reel member 6, is substantially circular in cross section, has the longitudinally extending bar members 9 thereof secured at their unsupported ends to an internal reinforcing ring 26 and at their supported ends to an external annular rib 27. Rib 27 is secured to eccentrically mounted supporting member 28 by means of bolts 29.

Supporting member 28 embodies a concave web portion 30 and a projecting sleeve portion 31, of which the latter is mounted about a boss 38 formed on frame member 36. The axis of bore 37 of boss 38 through which shaft 19 projects is offset from and inclined to the axis of shaft 19. Sleeve portion 31 of supporting member 28 is mounted concentrically of boss 38 by means of spaced anti-friction bearings 32. Thus reel member 1 is rotatably mounted with its axis in offset and inclined relation to the axis of reel member 6 which, as previously explained, is supported by closure members 13 and 14 concentrically of shaft 19.

By means of snap rings 33 the outer races of bearings 32 are held in properly spaced relation to each other in sleeve portion 31 of supporting member 28. The inner race of one of the bearings 32 is held in place against a shoulder on hub 39 of boss 38. The inner race of the other bearing 32 is held in place by a washer 34 secured to the forward end of boss 38 by a machine screw 35.

Frame member 36 embodies boss 38, hub 39 and transverse coupling 42 spaced from and secured to hub 39 by means of parallel longitudinally ex-

tending arms 41. Supported transversely of and between arms 41 at a point approximately midway between boss 38 and coupling 42 is a flange 43. Flange 43 is employed for the purpose of mounting the reel unit as a whole in apparatus embodying a plurality of similar units in the manner shown, described and claimed in George P. Torrence et al. Patent 2,217,716.

Shaft 19 extends lengthwise of frame member 36, passing through bore 37 of boss 38 and projecting beyond coupling 42. Shaft 19 is journaled in anti-friction bearings 44 and 45 mounted in hub 39 of boss 38 and in coupling 42, respectively. The outer race of bearing 44 is pressed into a socket in hub 39 and the inner race is held in place by means of collar 46 secured to shaft 19. The outer race of bearing 45 is pressed into the bore of coupling 42 against a felt-ring 47 held in place by a suitable snap ring. The inner race of said bearing is located in place by collar 48.

By virtue of its substantially frictionless mounting, shaft 19 may be actuated with a minimum of driving force. The wide spacing of bearings 44 and 45 greatly minimizes the degree of flexing of that portion of shaft 19 which projects beyond boss 38 of frame 36; that is to say, that portion which supports reel member 6. Bevel gear 50, which is secured to shaft 19, may be located at any convenient point between flange 43 and coupling 42. It provides positive driving engagement with the driving member of the apparatus to which the unit as a whole is applied.

In the interior of cylindrical body portion 11 of reel member 6 directly back of rear closure member 14 is disposed an annular internally toothed member 51 secured thereto by means of a plurality of flat-head screws 52. Internally toothed member 51 engages a series of teeth 53 formed integrally upon the exterior of sleeve portion 31 of supporting member 28. As shaft 19 is rotated by gear 50, reel member 6 positively actuates reel member 7 through the intermeshing of internally toothed member 51 and teeth 53 and at the same time maintains bar members 8 and 9 of reel members 6 and 1, respectively, in spaced relation.

Positive maintenance of the spaced relation between bar members 8 and 9 is desirable in certain types of reels, particularly those employed in drying thread. Drying reels commonly require that the reel members thereof be fabricated of metal or other suitable material possessing a high heat conductivity. Aluminum and various alloys of aluminum have been found to be most satisfactory for this purpose; but since such materials are comparatively soft, abrasion caused by contact between adjacent bar members would soon result in damage to the reel.

Secured to coupling 42 of frame member 36, as by means of bolts 54, is a stationary member 55 which facilitates the supply of drying medium to and its removal from the reel. Stationary member 55 comprises two internal compartments; namely, intake chamber 56 and exhaust chamber 57. A seal plate 58 and gasket 59 are disposed between coupling 42 and stationary member 55 for the purpose of preventing leakage of drying medium therebetween.

Upon that portion of shaft 19 which projects beyond and to the rear of bearing 45 is secured, as by means of set screw 61, a rotatable sealing member 62. Two rings 63 and 63', preferably of carbon, synthetic rubber or the like, form part of rotatable sealing member 62 and provide contact

with the inner face of seal plate 58 and annular rim 64 of exhaust chamber 57, respectively. Between each of the rings 63 and 63' and the base of each oppositely disposed cylindrical bore 65 in rotatable member 62 is disposed flexible packing material 66 which is urged against said ring and base by coil spring 67, thus effectively preventing leakage between intake chamber 56 and exhaust chamber 57.

Hot water or some other suitable drying fluid is supplied to chamber 12 of reel member 6 by means of a hollow shaft 19 which communicates with said chamber 12 and intake chamber 56 of stationary member 55 through ports 68 and 69. Tube 71 disposed within the bore of shaft 19 connects chamber 12 with exhaust chamber 57 by means of ports 72 and 73 and serves to remove the drying medium from reel member 6. In this fashion, a constant flow of drying fluid is maintained through chamber 12 of reel member 6.

Wet thread which is being dried from the gel state; e. g., so-called freshly spun viscose artificial silk thread, possesses an inherent tendency to shrink in the course of the drying operation. In the use of a reel of the kind herein described, wet thread is applied to the periphery of the reel at a point near the supported end thereof and is advanced toward the unsupported end thereof in generally helical turns of substantially uniform circumference. If the thread is subjected to a drying operation during its advance along the periphery of the reel, it will attempt to shrink, thus introducing tension into the thread.

Under certain circumstances, this tension in the thread, although resisted by the reel structure, becomes so great as the thread nears the unsupported end of the reel that it causes the portion of the shaft projecting beyond the bearing support to become sprung. In effect, this brings the eccentric and concentric members into parallel relation, thus destroying the inclination between their respective axes with the result that the thread turns no longer will be advanced along the reel. The banding of thread turns which follows causes a permanent bending of the shaft, effecting frictional contact between the bar members of the respective sets as well as excessive wear on the internal and external gears 51 and 53.

The present invention effectively eliminates any such flexing of the shaft by providing a wide spacing of the bearing means, this by positioning one of said bearing means internally of the reel.

Although the reel hereinabove described constitutes the preferred embodiment of the invention, at least at the present time, it will be apparent that numerous modifications may be made therein without departing from the spirit of the invention. Thus flange 43 in frame member 36 may, if desired, be interchanged with gear 50. Similarly, bearing 44 may, if desired, be positioned at the very end of boss portion 38 of frame 36. Other changes within the purview of the invention will readily suggest themselves to those skilled in the art.

It is intended that the patent shall cover, by suitable expression in the appended claims, whatever features of patentable novelty reside in the invention.

What is claimed is:

1. Means for supporting a thread-advancing reel embodying two sets of bar members disposed in inclined relation to each other comprising a frame member; means for supporting one of said sets of bar members from a point within its own periphery for rotation about one end of said

frame member; first bearing means substantially completely encompassed by the supporting means for said first set of bar members disposed adjacent the end of said frame member about which 5 said first set of bar members is mounted; second bearing means disposed adjacent the other end of said frame member; a shaft journalled in and extending beyond said first bearing means, the second set of bar members being mounted upon the projecting portion of said shaft; and driving means mounted upon the shaft between said first and second bearing means.

2. Means for supporting a thread-advancing reel embodying two sets of bar members disposed 10 in inclined relation to each other comprising a frame member one end of which terminates in a boss portion; means extending inward of the device as a whole for supporting one of said sets of bar members for rotation about said boss portion; first bearing means disposed in said frame member adjacent the boss portion thereof, said bearing means being substantially completely encircled by said supporting means; second bearing means disposed adjacent the opposite extremity 15 of said frame member; a drive shaft journalled in said bearing means extending through the boss portion of said frame member, the other of said sets of bar members being mounted upon the projecting portion of said shaft; and driving means 20 mounted upon said shaft between said first and second bearing means.

3. Means for supporting a thread-advancing reel embodying two reel members which cooperate to form the thread-bearing periphery thereof 25 comprising a frame member one end of which terminates in a boss portion; means extending inward of the reel as a whole for supporting one of said reel members for rotation about said boss portion; first bearing means disposed in said frame member adjacent the boss portion thereof, said bearing means being substantially completely encircled by said supporting means; second bearing means disposed adjacent the opposite extremity 30 of said frame member; a drive shaft journalled in said bearing means extending through the boss portion of said frame member, the other of said reel members being mounted upon the projecting portion of said shaft; and driving means 35 mounted upon said shaft between said first and second bearing means.

4. Apparatus according to claim 3 in which at least one of said bearing means is an anti-friction bearing.

5. Apparatus according to claim 3 in which both of said bearing means are anti-friction bearings.

6. Apparatus according to claim 3 in which said first bearing means are disposed at a point between said mounting means and that end of the frame member which terminates in said boss portion.

7. Apparatus according to claim 3 in which said driving means are mounted upon the shaft between said mounting means and said second bearing means.

8. Apparatus according to claim 3 in which said first bearing means are disposed at a point within the periphery of the said thread-advancing reel.

9. Thread-handling apparatus comprising a frame member having spaced bearing means disposed adjacent the extremities thereof; a shaft journalled in and extending beyond said bearing

means; a thread-advancing reel characterized by two interdigitating sets of spaced, longitudinally extending bar members of which one set is mounted upon one of the projecting ends of said shaft in rotatable relation to said frame member while the other is rotatably supported about one end of said frame member in such manner as to substantially completely encompass the bearing means adjacent that end of the shaft upon which said first-mentioned set of bar members is mounted; mounting means intermediate the ends of said frame member; and, driving means mounted upon said shaft between said bearing means.

10. Apparatus according to claim 9 in which at least one of said bearing means is an anti-friction bearing. 15

11. Apparatus according to claim 9 in which both of said bearing means are anti-friction bearings.

12. Apparatus according to claim 9 in which 5 said mounting means are disposed between the driving means and the bearing means adjacent that end of the shaft upon which said first-mentioned set of bar members is mounted.

13. Apparatus according to claim 9 in which 10 the bearing means adjacent that end of the shaft upon which the first-mentioned set of bar members is mounted are disposed at a point within the periphery of said thread-advancing reel.

14. Apparatus according to claim 9 in which said mounting means are disposed between said bearing means.

RICHARD F. BERGMANN.
